UNITED STATES PATENT OFFICE.

CHARLES HERBERT DRAPER, OF CLEVELAND, OHIO, ASSIGNOR TO THE DRAPER MANUFACTURING COMPANY, OF CLEVELAND, OHIO, A CORPORATION OF OHIO.

SHEET-METAL CONTAINER.

1,303,175.

Specification of Letters Patent.

Patented May 6, 1919.

Application filed February 18, 1916. Serial No. 79,316.

To all whom it may concern:

Be it known that I, CHARLES HERBERT DRAPER, a citizen of the United States of America, residing at Cleveland, in the county of 5 Cuyahoga and State of Ohio, have invented certain new and useful Improvements in Sheet-Metal Containers, of which the following is a specification.

My invention relates to improvements in 10 metal containers, and more particularly to sheet-metal barrels with removable closures. The object of my invention is to provide a metal container which shall be cheap to manufacture, readily opened and closed, un- 15 obstructed at the mouth, and exceedingly simple in its closure members. The device of my invention, shown in several modified forms, in the accompanying drawings, admirably meets these and other practical re- 20 quirements, and permits of continued use of a metal receptacle, especially adapted for heavier liquids and solids, over long continued periods, while permitting thorough cleansing of the interior of the receptacle 25 at any time it is empty for refilling.

The sheet-metal barrel herein set forth, as 30 an embodiment of my invention, is comprised of a cylindrical body-portion, preferably ribbed midway to provide a bilge, and suitably formed at its mouth or opening 35 to accommodate the closure members. These closure members preferably comprise a dished circular head, insertible within the mouth of the barrel, and a split resilient ring adapted to engage respectively, an overturned or flanged portion about said mouth, and exert peripheral pressure upon the closure member. Optionally, the barrel mouth and its closure part may be stiffened 40 or separately reinforced and fitted to interlock more or less completely, for effecting the sealing relation between these members.

Further details of my embodied invention, its adaptation and advantages, may be 45 ascertained by making reference to the accompanying drawings, wherein:—

Figure 1 is a view in elevation partially 50 broken away, of a sheet-metal container, its closure part and retaining ring, embodying my invention; the latter being in position of removal from the mouth of the barrel.

Fig. 2 is an enlarged fragmentary detail, 55 partially broken away, and in section, showing the structure of the barrel mouth and closure members.

Figs. 3 to 6 inclusive, are similar fragmentary views in section, setting forth certain modifications of the embodied principle of construction, depicted in Figs. 1 and 2.

Throughout the several figures of the 60 drawings I have employed the same character of reference to indicate similar parts.

The body, *a*, of the container, may be made of any suitable or desired form, but preferably it is cylindrical and centrally 65 rolled to provide two enlarged convex ribs, *b*, *b*, which serve as the bilge or rolling support for the barrel. The mouth of the container is very simply shaped, to afford a 70 terminal retaining flange, and an inner annular rib or seat, for accommodating the closure part. As the retaining member may be cheaply and readily manufactured from round rod, I preferably roll the mouth of 75 the barrel to approximately a half-round, as shown in the several figures of the drawings. Being thus shaped to inclose approximately one-half the periphery of the retaining member, the closure part *e* is so shaped 80 and disposed as to be engaged by said member peripherally in position beyond its diameter in cross section.

Referring still to Figs. 1 and 2, the terminal flange *c*, is formed closely adjacent to an annular seat or rib *d*, whereon the closure 85 part *e*, is adapted to bear. This closure part is dished, a *d* has a spun inwardly protruding rim *f*, approximately of the same curvature, as that of the terminal flange *c*. When the closure is inserted within the mouth of 90 the receptacle, the split ring *g* is adapted to be forced to its retaining position against the inherent spring of the metal forming the barrel body and the closure, and will readily find its seat beneath the flange *c*, in the half-round recess, provided therefor, with its ends sprung almost into engagement. The parts if accidentally misshapen, may readily 95 be seated by rapping upon the half-round with a mallet, and thus the closure part is 100 held securely in place, until the split ring is removed.

In the construction of Fig. 3, the closure part *e*, is slightly modified, to provide a depending rim *e'*, which conforms approximately to the modified seat or inner rib, *d'*, while a gasket *h*, is interposed to afford a more perfect seal, than is afforded by metal to metal, under moderate pressures. The in-turned rim *e''*, also is straight instead of 110

curved in cross-section, but otherwise the parts are just as previously described.

The structures shown in Figs. 4 and 5, contain features in common with those just described, but the closure part *e*, (Fig. 4), is reversed in position to secure its edgewise engagement with the gasket *h*, disposed in the recessed annular seat *d'*. In Fig. 5, moreover, the annular edges, both of the barrel body and closure part, are overturned to afford additional stiffness, in case a relatively light gage of metal is employed for constructing the container.

Fig. 6 discloses a container constructed upon the principles already defined, but reinforced by a separate and suitably formed sleeve, *i*, affixed within the mouth of the container. This reinforcing member is provided with a lower annular lip *i'*, bent back to afford a sealing recess for the edge of the dished closure part, while the overturned edge *i''*, forms a double locked seam, about the mouth of the container, thereby strengthening and reinforcing said mouth, while affording a somewhat better, or more effective seal, for the closure part, than is obtainable in the structures of Figs. 2 and 5, for example.

I am aware that closure parts previously have been provided with retaining rings dependent upon more or less positive expansive means for securing them in position. In the devices of my invention, however, no expansion of the ring is necessary, nor is such action depended upon in any way for retaining the closure in place. On the contrary, the mouth of the container and the closure are so shaped and related or proportioned, as to inclose and bear peripherally upon the retaining member at points more than 180° apart cross-sectionally, thereby coacting to hold all the members in sealing relation. It is apparent that with the constructions shown, the continuity and resilience of the retaining member or members are of minor importance, since the cross-sectional conformation to the recess therefor, formed by the half-round bead and the closure, alone is relied upon for retaining the parts in separable operative relation.

It is apparent, from the foregoing description, that the modified structures may be still further altered, in accordance with the principles of operation disclosed, without departing from my invention.

Having now described the preferred embodiment of my invention, I claim as new, and desire to secure by Letters Patent, the following:—

1. A metal container, comprising a cylindrical sheet-metal body-portion, having a circumferential flange about its mouth or opening, and provided with an annular seat adjacent to said flange, a disk-like closure part, adapted to fit tightly upon said seat,

and a split annular member removably positioned beneath the flange in such relation when seated as to be engaged peripherally at widely separated points by the flange and closure respectively and thereby forced to its seat, substantially as set forth.

2. A metal container, comprising a sheet-metal body-portion, having a flanged cylindrical mouth or opening, and a seat for the closure part adjacent thereto, a circular closure part adapted to be forced against said seat, and a split annular member fitting tightly beneath said flange, to bear upon the closure part, and removably hold it against its seat in the mouth of the container, said retaining member when seated being positioned peripherally to be engaged by the flange and closure part at points tending to force it to its seat, substantially as set forth.

3. A metal container, comprising a cylindrical body-portion, provided at its top with an exteriorly half-round circumferential flange, and an adjacent inwardly extending rib, a dished circular closure part fitting removably against said rib, and a retaining member round in cross-section fitting beneath said flange, and bearing upon the closure part along its inner periphery at points tending to force it to its seat within the half round flange, whereby the closure part is removably held against said rib, substantially as set forth.

4. A metal container, comprising a body-portion, having a cylindrical mouth or opening terminally rolled to form an exteriorly rounded bead, and an adjacent inwardly projecting annular rib, a dished circular closure part fitting within the opening, and engaging said rib, and a retaining member round in cross-section fitting within the bead, and bearing peripherally against the closure part, to hold the same removably in sealing relation against the rib, said retaining member when seated being positioned peripherally to be engaged by the extreme lip of the bead and the closure respectively at points tending to force it to its seat, substantially as set forth.

5. A metal container, comprising a cylindrical body-portion terminally rolled to provide an exteriorly convex rib and an adjacent interiorly projecting annular rib, a circular closure member adapted to fit tightly against said interiorly extending rib, and a split ring fitting interiorly within the exteriorly projecting rib, and bearing upon the closure part and exterior rib along its inner periphery at points displaced cross-sectionally less than 180° to hold the ring tightly against its seat, substantially as set forth.

6. A metal container, comprising a cylindrical body-portion terminally rolled to provide an exteriorly convex half-round bead

and an adjacent interiorly projecting annular rib, and a circular closure part adapted to be engaged by said rib, a retaining member round in cross-section adapted to fit 5 within the bead; said retaining member when seated being positioned peripherally to be engaged by the bead and closure part along bearing surfaces tending to force it to its seat, substantially as set forth.

10 7. A metal container comprising a body portion having a cylindrical mouth or opening, the same being rolled to afford a terminally disposed exteriorly rounded flange, and an adjacent inwardly projecting rib, a 15 dished circular closure-part fitting within said mouth against the rib, and a retaining

member substantially round in cross-section to conform with the flange and being positioned when seated therein to be engaged along its inner circumference by the terminal lip of the flange and the closure respectively at points displaced less than 180° , whereby it is caused to find its seat within the flange and hold the parts in sealing relation, substantially as set forth.

20 25 In testimony whereof I do now affix my signature in the presence of two witnesses.
